ERNEST J. BRASSEUR, OF CHICAGO, ILLINOIS, ASSIGNOR TO A. B. DICK COMPANY, OF CHICAGO, ILLINOIS, A CORPORATION OF ILLINOIS

SHEET MANIPULATOR

Application filed November 14, 1928. Serial No. 319,224.

This invention relates to sheet manipulators and more particularly to a device adapted to be attached to a typewriter or other form of writing machine and operative to grip a sheet of writing material positioned in the machine and advance the same evenly and accurately, so that all lines of writing appearing on the sheet are properly spaced and in accurate parallelism.

10 The device forming the subject matter of this invention is especially designed for ready attachment to and detachment from the ordinary typewriter to move the backing sheet on which a stencil paper is mounted evenly and by stages through the typewriter as the typewritten lines are placed thereon.

15 In the use of writing machines such as the ordinary typewriter, for instance, difficulty is constantly encountered in obtaining written lines which are always in complete parallelism and properly and accurately spaced. There is very apt to be some slippage between the sheet and the feed roller of the typewriter to skew the sheet to one side as it progresses 20 through the machine. Again, the sheet may be slightly misadjusted in relation to the type, following erasures on the sheet, or from other causes. These inaccuracies become more evident when ruled paper is used, as 25 is often necessary in preparing charts, reports, etc. The result is a slovenly and unsightly piece of work.

30 This problem is much enhanced when a stencil sheet is being typed and prepared to be later placed on a stencil duplicating machine. All errors and inaccuracies occurring on the stencil sheet such as lack of parallelism and proper spacing of the written lines will 35 be reproduced on each mimeographed copy.

40 The principal object of my invention is to provide means for advancing a sheet through a writing machine by stages and in such a manner that the written lines appearing on the sheet will be properly and accurately 45 spaced and will be in accurate parallelism.

Another object of my invention is to provide a sheet moving device adapted to be readily and easily attached to and detached from typewriters in common use, operative to 50 draw the sheet evenly and accurately

through the machine, and one which is simple and easy to operate, positive in its operation, of sturdy and durable construction, and inexpensive to produce.

A well known index system employs very 55 narrow separate strips of cardboard on which the indicia are printed. In certain systems it has been customary to use strips of about one-sixth of an inch in width by about five inches in length. Thus it is at once apparent that when these strips are printed by means of a stencil there must be precise registration and parallelism of each line on the stencil with each strip or else all of the printing will not be imprinted on the respective 60 strips. In one system the blank from which these strips are obtained comprises a card which has been partially cut through in parallel lines spaced apart the width of each strip. Usually the card is as wide as the 65 strips are to be, the length depending upon how many strips are desired.

More specifically an object of my invention is to provide an attachment for typewriters 70 whereby a stencil may be prepared, in which the lines impressed therein will correspond exactly in parallelism and spacing with the strip areas in a card or blank of the type referred to, so that when the stencil is used for printing such cards, each strip thereof will 75 receive all of the intended imprint properly 80 centered and registered thereon. After the card or blank has been printed the strips thereof are torn apart at the weakened lines 85 which separate the strips, and the strips are used as desired. Accordingly the importance of providing for precise registration of the printing on each card is apparent.

A further object of this invention is to provide a novel stencil unit whereby the attainment of accuracy and precision in the placement of impressions on the sheet and accurate and precise registration of stencil imprint on the work is enhanced.

90 Other objects of this invention will be in part obvious and in part pointed out hereinafter.

In accordance with this invention I provide 95 stenciling material comprising a stencil sheet 100 secured along one edge to a backing sheet

which extends beyond the stencil sheet along both sides. Along each projecting side of the backing sheet is a row of holes uniformly spaced apart.

5. Heretofore, it has been customary to clamp the stencil sheet between the platen roll and pressure rolls and to advance the sheet by rotating the platen, thus relying wholly on the frictional engagement of the material 10 with these rolls to maintain the material in alignment and to obtain the spacing between lines. As aforesaid, it has been found that when accurate and precise alignment and spacing are desired such frictional agency is 15 not reliable for the purpose. Accordingly, I provide means for maintaining alignment and spacing which does not depend on a frictional engagement, but instead provide means which positively engage and hold the sheet 20 and which direct and govern its movements for spacing. Such means may comprise pins which engage in corresponding holes along each side of the backing sheet, means being provided for reciprocating the pins in unison 25 and to the same degree on both sides of the backing to advance both sides of the stencil- 30 ing material exactly the same distance, the pins being so mounted that they can be withdrawn from one set of holes and engaged with succeeding holes in the rows to advance 35 the material. Preferably the pressure rollers of the typewriter are left open so that in case the operator should rotate the platen, no strain will be put on the stenciling material. 40 Otherwise, the typewriting of the stencil and the movement of the carriage are accomplished in the usual manner. The device is so constructed that it may be attached to and dismounted from a typewriter of a usual make, readily and easily.

In order that a clearer understanding of this invention may be had, attention is hereby directed to the accompanying drawings, forming a part of this application and illustrating certain possible embodiments of this invention.

Referring to the drawings, Fig. 1 is a front face view of my sheet manipulator attachment;

50. Fig. 2 illustrates a sheet of material and more particularly a stencil sheet mounted on a backing sheet, the backing sheet having a row of holes along each side edge thereof with which the reciprocating arms of my 55 sheet manipulator are adapted to engage to advance the sheet by stages over the platen of the typewriter;

Fig. 3 is a transverse cross sectional view of my combined stencil sheet and backing 60 therefore, taken on line 3—3 of Fig. 2;

Fig. 4a is a transverse cross sectional view of my sheet manipulator attachment and certain parts of a typewriter with which it co- 65 operates, taken on line 4—4 of Fig. 1 and illustrates more particularly the position of

the parts at the completion of a sheet advancing operation;

Fig. 4b is a view similar to Fig. 4a and illustrates the position of the parts at another stage of operation, particularly showing one of the sheet engaging arms out of engagement with the sheet being fed and about to be moved downwardly to again engage the sheet.

Fig. 4c is a view similar to Figs. 4a and 4b and illustrates the position of the parts at still another stage of operation, particularly showing one of the sheet engaging arms in engagement with the sheet being fed and about to advance the same;

Fig. 5 is another transverse cross sectional view of my sheet manipulator attachment in conjunction with certain typewriter parts, taken on line 5—5 of Fig. 1 and shows the opposite side of certain of the operative elements shown in Figs. 4a, 4b and 4c;

Fig. 6 is still another transverse cross sectional view of my sheet manipulator attachment in association with certain typewriter parts, taken on line 6—6 of Fig. 1;

Fig. 7 is a fragmentary cross sectional view taken on line 7—7 of Fig. 1 and shows particularly the spring pressed levers for manually operating my sheet manipulator attachment;

Fig. 8 is another transverse cross sectional view of my sheet manipulator attached to typewriter structure, taken on lines 8—8 of Figs. 1 and 9 respectively and illustrates one way of attaching the same to the typewriter;

Fig. 9 is a fragmentary sectional view taken on line 9—9 of Fig. 8 further showing the manner in which my sheet manipulator is attached to the typewriter structure;

Similar reference characters refer to the same parts throughout the specification and drawings.

I have shown my sheet manipulator associated with certain structural parts of a "Royal" typewriter but it is understood that my manipulator can be applied to any make of typewriter or writing machine within the purview of this invention. Referring more particularly to Fig. 6, I have shown a portion of the carriage frame 1 of the typewriter machine supported for horizontal sliding movement on the stationary frame 2. The carriage frame includes a pair of end members 4, one at each end thereof and reenforcing bars 5 and 6 extending between the end members to give the necessary stiffness to the carriage frame. The platen roll 3 of the typewriter is rotatably supported in the end frames 4. Inclined plate 7 supports the sheet 8 being fed under the platen roll of the machine. Plate 7 is supported at each end thereof by a bracket 9 suitably secured to the carriage frame. A horizontal frame member 10, secured to the end frames 4, carries a pair of curved guide arms 11 which guide the sheet around the

100

105

110

115

120

125

130

platens roll. Pressure rollers 12 and 13 are provided to retain the sheet against the platen roll. Type arms 14 are manipulated by means of a keyboard in a well known manner.

5 Referring more particularly to Figs. 1, 6 and 8, my construction may be said to comprise the sheet manipulator unit and means for detachably supporting this main unit in operative position on a typewriter.

10 For the supporting means I provide a pair of arch members 22 having flat supporting surfaces at their tops. To one end of each arch member is secured a clamping plate 23 and to the other end of each arch member is secured a clamping plate 24. These arch members are adapted to be secured to the typewriter carriage just inside of the end frames 4. One end of each arch member and its cooperating clamping plate 23 are adapted 15 to be engaged against opposite sides of the reinforcing bar 6 of the machine, adjacent its ends, and may be tightly clamped thereagainst by means of screws 25. The clamping plates 24, which are secured to the other legs 20 of the arch members, have end flanges 26 which are adapted to engage under the frame bar 10 while the ends of the arch members engage against the opposite side of member 10. These clamps grip the member 10. 25 Screws 27 penetrating the clamp plates 24 and engaging a shoulder 10' of the frame member, confine the ends of the arch members against downward movement and tighten the engagement.

30 It will be apparent that these arch members being located just inside of the end frames 4 of the carriage do not interfere in any way with the typewriter parts, and therefore these arch members may be allowed to 35 remain permanently on the typewriter.

The main portion of the sheet manipulator is adapted to be mounted quickly and easily on these arch supports, and to be as readily and easily removed. The main manipulator unit has end brackets 28 which have flanges 28' adapted to seat on the flat top portions of the arch supports, the flanges having perforations adapted to receive studs 22' carried on the top of the arch members, and having 45 perforations adapted to register with threaded screw apertures in the arch members.

To further steady and support the manipulator unit, recessed flanges 31 are turned in 50 from the brackets 28, these brackets being adapted to engage in grooves of studs 32 secured to the arch members 22.

55 My manipulator may be attached to a typewriter by merely engaging the brackets 28 with the studs 22' and 32 of the arch members, and engaging screws in the screw apertures. The manipulator may be removed by merely removing these screws and lifting the manipulator from the arch supports.

60 Each bracket 28 has an inclined flange 30 to

which the main plate 20 of the manipulator is secured by means of bolts 29, these preferably extending through slots in the plate 20 to permit of adjustment of the plate toward and from the platen roller of the typewriter to which this plate 20 is tangentially disposed so as to receive the sheet as it leaves the platen roller.

A plurality of rollers 34 journaled on a rod 35 guide the sheet from the platen roller to the guide plate 20. Rod 35 is hung on a pair of arms 36 which are secured to a shaft 37 journalled in lugs 38 projecting upwardly from the guide plate. Coil springs 39, one secured to each lug 38, exert a downward pressure on its corresponding arm 36, holding the rollers 34 against the platen roller with resilient pressure.

The lower edge of the guide plate 20 is preferably given an arcuate form, as clearly shown in Fig. 1. To support the center portion of the sheet, a tab 40 is secured to the guide plate 20. The sheet is confined between the guide lugs turned up from plate 20.

45 My sheet advancing mechanism is designed to advance the sheet over the platen roller by stages of predetermined lengths, and to hold the sheet in fixed position on the platen roller during the typing operation, so that the respective typewriter lines are in complete and accurate parallelism and spaced exactly as desired. My preferred form of advancing mechanism comprises generally a pair of reciprocating arms 42, each having a pin 43 secured to the end thereof. Each pin is adapted to be inserted in corresponding holes or apertures along each side edge of the sheet. Reciprocation of the arms 42 in one direction pulls or advances the sheet over the platen roll a predetermined amount herein called a 50 stage. Pins 43 are then lifted from their respective holes in the sheet and the arms reciprocated in the other direction to place the pins in engagement with another set of holes. The sheet is then advanced through another 55 stage as above described.

The mechanism for performing these operations will now be described. A shaft 44, extending horizontally of the machine, as shown in Figs. 4a, 4b and 4c, is journalled in a pair of lugs 45 secured to the under side of the guide plate 20. A pair of arms 46, one end of each being fixed to shaft 44, extend upwardly through suitable apertures in the guide plate. A rod 47 is journalled in the upper ends of these arms 46. One end of each of the reciprocating or sheet engaging arms 42, as shown in Fig. 1, are secured to rod 47. Elongated apertures 48 are provided in the guide plate into which the respective sheet engaging pins 43 on the end of the reciprocating arms extend. A pair of coil springs 49, one secured to each of the arms 46, exert a downward pressure on its corresponding reciprocating arm 42 to nor- 60 65 70 75 80 85 90 95 100 105 110 115 120 125 130

normally retain the pin in the end thereof in engagement with the paper.

A manually operated thumb lever 50 extending through a suitable aperture in the guide plate, is secured to one end of shaft 44. A coil spring 51 one end of which is secured to a stud 52 fixed to the guide plate, and its other end secured to one of the arms 46, exerts an upward pull thereon and normally retains the pins 43 in the upper portions of their respective slots 48, as shown in Fig. 4a. By rocking thumb lever 50 downwardly pins 43 can be moved to the other end of their slots, against the action of coil spring 51.

15 A finger lever 53 positioned in close proximity to the thumb lever above described is secured to one end of rod 47. By rocking finger lever 53 the pin ends of reciprocating arms 42 can be raised against the action of 20 coil springs 49. It is now seen that means are provided for raising and lowering the pin ends of the sheet engaging arms 42 into and out of engagement with the sheet and further for reciprocating these arms to 25 alternately advance the sheet and carry the pin ends of the arms into engagement with another set of holes in the sheet.

A lock device is provided to prevent downward movement of the sheet engaging arms 30 except when their pin ends are raised out of engagement with the holes in the sheet. As shown more clearly in Figs. 4a and 5, a limb 54 is secured to and projects from one of the arms 46. Limb 54 has a pin 55 projecting laterally therefrom.

40 A locking bar 56 pivoted at one end to one of the guide lugs 41 upturned from the guide plate, is provided with a deformed end adapted to abut against the pin 55. The deformed end of the locking bar is normally held in pin 45 abutting position by a coil spring 57 which is secured to guide lug 41 and operates to exert a downward pressure on the locking bar. The deformed end of the locking bar is retained in operative relationship with the pin by finger portion 58. An ear portion 59 formed integrally with the locking bar, extends over the sheet engaging arms 42. Manipulation of finger lever 53 rocks arm 42 50 about the axis of rod 47 so as to raise the sheet engaging pin, and raises the locking lever 56 (against the action of coil spring 57) by engagement of arm 42 with ear 59 out of locking engagement with the pin 55, 55 thus permitting downward movement of the thumb lever 53 and the sheet engaging arms.

My sheet manipulator attachment is of special value for example in the preparation of mimeographed copies of reports, index 60 files or cards, where it is of prime importance to have the mimeographed lines in accurate parallelism and properly spaced. For this purpose a stencil sheet of special construction is provided, as shown more clearly in Figs. 65 2 and 3. A sheet of stencil paper 60 of the

proper size is glued along one edge, as at 61, to a sheet of backing material 62, preferably tough strong paper. The backing sheet is provided with a row of holes or apertures 63 at each side edge thereof. The rows 70 of holes should be spaced the same distance apart as the sheet engaging pins 43 of the sheet manipulator. It is essential that the corresponding holes in the respective rows be spaced the same distance apart to insure 75 complete parallelism of the lines. The distance between successive holes in the respective rows should be the same as the desired line spacing or a fraction thereof, so that by advancing the backing sheet by means of 80 the sheet engaging arms a distance equal to the distance between one or more successive holes, the desired line spacing may be attained. If different line effects and a variety of spacings are desired, it is only necessary 85 to space the holes in the backing sheet accordingly. The free corners of the stencil paper are each provided with a hole 64 for a purpose hereafter to be described. The backing sheet 62 has a tear line 65 therein, so that 90 the left hand portion of the backing sheet as shown in Fig. 2 can be torn off from the right hand portion when the typing work on the stencil paper has been completed.

95 The entire duplicating operation may be described as follows. The stencil paper, as shown in Fig. 3 is preferably prepared especially for the use in hand, the holes 63 being spaced so as to correspond with the desired line spacing of the printer matter. My sheet 100 manipulator is applied to the typewriter in the manner heretofore described. The stenciling material, including the stencil sheet 60 and backing 62 secured together, is threaded through the typewriter by sliding the 105 paper down over plate 7 and around the platen roll 3. The paper is advanced forward on to portion 21 of the guide plate 20. The sheet engaging arms 42 are then raised by manipulating finger lever 53, and the paper again advanced sufficiently to permit 110 pins 43 on the end of the sheet engaging arms to be inserted in the proper corresponding holes along each side edge of the sheet.

115 When the sheet advancing mechanism is in at-rest position, the pins 43 abut the upper ends of their respective slots 48, as shown in Fig. 4a, and they are so held by the action of coil spring 51. In order to advance the sheet through one stage finger lever 53 is first manipulated, raising the pin ends of the sheet engaging arms 42 against the action of coil 120 springs 49, as shown in Fig. 4b. Any raising of the arms 42 also raises the deformed end of locking bar 56. The locking bar can thus be raised out of engagement with pin 55, and the thumb lever 50 manipulated to swing the sheet engaging arms downwardly against the action of coil spring 51. Sheet engaging 125 pins 43 can thus be positioned over the next

set of holes in the stencil paper backing. Thumb lever 53 is then released permitting the pins to engage corresponding holes in the backing sheet, as shown in Fig. 4c.

When finger lever 50 is released, coil spring 51 acts to pull the sheet advancing mechanism upward, dragging the stencil paper with it. During this operation pins 43 move from the lower ends of slots 48 to the upper ends thereof. The stencil paper has now been advanced through one complete stage. The typing operation can be begun at any point of the stencil sheet desired, and when a line of writing has been completed, the stencil paper can be advanced by my sheet manipulator in the manner above described. The lines of writing 81, 82 and 83 appearing on the stencil sheet as shown in Fig. 2 now appear in accurate parallelism and spaced exactly as desired.

The stencil paper is now removed from the typewriter and sheet manipulator attachment. The backing sheet is now torn along its weakened line 65 and the right hand portion of the sheet shown in Fig. 2 discarded. The holes 63 in the left hand portion of the sheet are designed to secure the sheet upon the drum of a duplicating machine, not shown.

As many changes could be made in the above construction, and many apparently different embodiments of this invention could be made without departing from the scope thereof, it is intended that all matter contained in the above description or shown in the above drawings should be interpreted as illustrative and not in a limiting sense.

What I claim is:—

1. A typewriter attachment of the character described, including, in combination, a frame adapted to be secured to the typewriter, sheet-engaging members mounted on the frame for movement into and out of engagement with both sides of a sheet positioned in the typewriter for printing, and movable on the frame along the path of travel of the sheet through the typewriter to advance both sides of an engaged sheet uniformly.

2. A typewriter attachment of the character described, including, in combination, a frame adapted to be secured to the typewriter, sheet-engaging members, and means supporting said members on the frame for movement into and out of engagement with both sides of a sheet positioned in the typewriter for printing, and for reciprocation along the path of travel of the sheet through the typewriter, and means for moving said members into and out of engagement with such sheet and for reciprocating said members to advance a sheet through the typewriter and maintaining positive alignment thereof.

3. A typewriter attachment of the character described, including, in combination, a

frame adapted to be secured to the typewriter, a member having sheet engaging means, said member being movable on the frame into and out of position engaging a sheet in the typewriter, and bodily translatable to advance an engaged sheet through the typewriter.

4. A typewriter attachment of the character described, including, in combination, a frame adapted to be secured to the typewriter, a sheet advancing and aligning device carried on the frame and having sheet engaging means, said device being mounted on the frame for reciprocation along the path of travel of a sheet through the typewriter, and adjustable on the frame into and out of engagement with both sides of a sheet positioned in the typewriter for printing, whereby when said device is engaged with the sheet and moved in the direction of the travel of the sheet through the typewriter, both sides of the sheet are positively advanced a like amount through the typewriter and both sides of the sheet are held fast in the advanced position until disengaged by said device.

5. A typewriter attachment of the character described, for advancing through and aligning in the typewriter sheets having similar perforations along both sides, including, in combination, a frame adapted to be secured to the typewriter, and means, including members movable on the frame into engagement with selected corresponding perforations on both sides of the sheet and movable on the frame in the direction of the path of travel of the sheet through the typewriter, for advancing both sides of the engaged sheet a like amount through the typewriter and maintaining both sides of the sheet in alignment while engaged by said members.

6. A typewriter attachment of the character described, including, in combination, a frame adapted to be secured to the typewriter, a member having sheet engaging means and movably mounted on said frame for adjustment into and out of engagement with a sheet positioned in the typewriter, and for reciprocation along the path of travel of the sheet through the typewriter, and manually operable means for controlling the adjustment and reciprocation of said member.

7. A typewriter attachment of the character described, including, in combination, a frame adapted to be secured to the typewriter, a member having sheet engaging means and movably mounted on said frame for adjustment into and out of engagement with a sheet positioned in the typewriter, and for reciprocation along the path of travel of the sheet through the typewriter, manually operable means for controlling the adjustment and reciprocation of said member, and means associated with said member and said manually operable means for preventing

initial reciprocal movement of said member in one direction, while said member is engaged with the sheet.

8. A typewriter attachment of the character described, including, in combination, a frame adapted to be secured to the typewriter, a member having sheet engaging means and movably mounted on said frame for adjustment into and out of engagement with a sheet positioned in the typewriter, and for reciprocation along the path of travel of the sheet through the typewriter, manually operable means for controlling the adjustment and reciprocation of said member, means associated with said member and said manually operable means for preventing initial reciprocal movement of said member in one direction, while said member is engaged with the sheet, and means whereby adjustment of said member out of engagement with said sheet releases said member for movement in said direction.

9. A typewriter attachment of the character described, including, in combination, a frame adapted to be secured to the typewriter, an arm pivotally mounted on the frame for reciprocation along the path of travel of a sheet through the typewriter, a sheet-engaging member pivotally mounted on said arm for reciprocation into and out of engagement therewith, and means associated with said arm and member whereby the movement of said member on said arm and the movement of said arm on the frame may be controlled manually.

10. A typewriter attachment of the character described, including, in combination, a frame adapted to be secured to the typewriter, an arm pivotally mounted on the frame for reciprocation along the path of travel of a sheet through the typewriter, a sheet-engaging member pivotally mounted on said arm for movement toward the sheet to engage the sheet, and for movement away from the sheet to disengage the sheet, said member being engageable with the sheet when the arm is in rearward position, said member and the sheet engaged thereby being advanced upon forward movement of said arm.

11. A typewriter attachment of the character described, including, in combination, a frame adapted to be secured to the typewriter, an arm pivotally mounted on the frame for reciprocation along the path of travel of a sheet through the typewriter, a sheet-engaging member pivotally mounted on said arm for movement toward the sheet to engage the sheet, and for movement away from the sheet to disengage the sheet, said member being engageable with the sheet when the arm is in rearward position, said member and the sheet engaged thereby being advanced upon forward movement of said arm, means preventing rearward movement of said arm from forward position while said member is in

sheet-engaging position, and means for disengaging said member from the sheet when said arm is in forward position.

12. A typewriter attachment of the character described, including, in combination, a frame adapted to be secured to the typewriter, an arm pivotally mounted on the frame for reciprocation along the path of travel of a sheet through the typewriter, a sheet-engaging member pivotally mounted on said arm for movement toward the sheet to engage the sheet, and for movement away from the sheet to disengage the sheet, said member being engageable with the sheet when the arm is in rearward position and disengageable from the sheet when the arm is in forward position, a detent normally engaging said arm when in forward position, preventing rearward movement thereof, and means, including said sheet-engaging member, whereby movement of said member out of engagement with the sheet moves said detent to release said arm for rearward movement from its forward position.

13. A typewriter attachment of the character described, including, in combination, a frame adapted to be secured to the typewriter, a pair of arms pivotally mounted on the frame at each side of a sheet positioned in the typewriter and reciprocable along the path of travel of the sheet through the typewriter, a member pivotally mounted on each arm for movement into engagement with the adjacent side of the sheet and for movement out of engagement therewith, and means associated with said arms and members and under manual control whereby both said members may be moved into engagement simultaneously with opposite sides of the sheet when said arms are in rearward position, and whereby both arms are simultaneously moved forward a like amount to advance both sides of the engaged sheet in like amount through the typewriter.

14. A typewriter attachment of the character described, including, in combination, a frame adapted to be secured to the typewriter, a pair of arms pivotally mounted on the frame at each side of a sheet positioned in the typewriter and reciprocable along the path of travel of the sheet through the typewriter, a member pivotally mounted on each arm for movement into engagement with the adjacent side of the sheet and for movement out of engagement therewith, means associated with said arms and members and under manual control whereby both said members may be moved into engagement simultaneously with opposite sides of the sheet when said arms are in rearward position, and whereby both arms are simultaneously moved forward a like amount to advance both sides of the engaged sheet in like amount through the typewriter, and means associated with said arms and sheet engaging members nor-

mally holding said arms in forward position and said members in position engaging both sides of said sheet.

15. In the art of advancing and securing alignment of a sheet in a typewriter or like printing machine, the combination of a sheet to be imprinted having a series of corresponding perforations along each side, members mounted on the typewriter, one at each side of the sheet and each having a pin fitting the sheet perforations, and mechanism associated with said members whereby said pins may be engaged simultaneously in selected corresponding perforations on both sides of the sheet and then moved forwardly along the path of travel of the sheet through the typewriter to advance both sides of the sheet a like amount, and maintaining the sheet in alignment while said pins are engaged in the corresponding perforations thereof.

20. This specification signed this 9th day of November, 1928.

ERNEST J. BRASSEUR.
